Patented Sept. 4, 1973

228,290

ELECTRONIC CALCULATING MACHINE

Sigetoshi Hazama, Osaka, Japan, assignor to
Sharp Kabushiki Kaisha, Osaka, Japan

Filed Jan. 12, 1972, Ser. No. 217,426

Claims priority, application Japan July 19, 1971

Term of patent 14 years

Int. Cl. D14—02

U.S. Cl. D26—5 C

Fig. 3

Fig. 2

Fig. 4

Fig. 7

FIG. 1 is a front perspective view of the electronic calculating machine showing my new design;

FIG. 2 is a plan view;

FIG. 3 is a front elevational view;

FIG. 4 is a rear elevational view;

FIG. 5 is a right side elevational view;

FIG. 6 is a left side elevational view; and

FIG. 7 is a bottom view.

I claim:

The ornamental design for an electronic calculating machine, as shown.
